Washington Societys of Portsmouth New Hampshire
Letters Patent

The schedule referred to in this Letter Patent and making part of the same, containing a description in the words of the said Washington Societys himself, of his improvement in the Traveling Trunks.

To all to whom these presents shall come:

Be it known that J. Washington Societys of Portsmouth County of Rockingham in the State of New Hampshire, have invented a new and useful improvement in the Traveling Trunks and that the following is a full and exact description thereof, namely, my improvement consists in covering the outside of the trunk with some metallic substance, Tin plate we have used as being the cheapest metal. The trunk fixed as completely covered with the sheet metal externally before the leather or skin are drawn on, the trunk is then covered with leather or skin and finished in the usual manner. What I claim as my invention or improvement is the covering the trunk for Traveling and other purpose, with tin plate, or some metallic substance and making it more safe and secure against fire from the burning of baggage cars on rail roads &c. it is also a safety in steaming weather against wet, not being liable to get to the inside of the trunk, and another advantage is it cannot be cut or injured as trunks in general are liable to. The said trunk in addition to its being made impervious to water &c. is externally surrounded or secured by iron, which renders it also unbreakable for strength.

Witness my hand this 1st day of July 1836
John Washington Societys
Dr. J. W. Wood
